CLAIM

The ornamental design for a housing for an electric outboard motor, substantially as shown and described.

DESCRIPTION

FIG. 1 is a right side elevational view of housing for an electric outboard motor, the opposite side is a mirror image thereof;

FIG. 2 is a top plan view thereof;

FIG. 3 is a bottom plan view thereof;

FIG. 4 is a rear elevational view thereof;

FIG. 5 is a front elevational view thereof; and FIG. 6 is a perspective view thereof, the view being taken generally from the right front upper side.
